The ornamental design for a human body detector, as shown and described.

DESCRIPTION

1. Human body detector

1.1 : Front

1.2: Back

1.3 : Left

1.4: Top

1.5: Bottom

1.6: Perspective

1.7: Perspective

1.8: Perspective

The claimed design is a human body detector, which is mounted on a support member, such as a wall or a pole, to detect human body by using infrared rays or microwaves; specifically, a rear part of the detector is attached to the
